(Cl. D44—29)

To all whom it may concern:

Be it known that we, respectively, Fritz Kahlen, a citizen of Germany, residing at New York, in the county of New York and State of New York, and Peter P. Jordan, a citizen of the United States of America, and residing at Jackson Heights, in the county of Queens and State of New York, have invented a new, original, and ornamental Design for a Combined Bottle Opener and Cork Remover, of which the following is a specification, reference being had to the accompanying drawing, forming a part thereof.

In the drawing,

Figure 1 is a front elevational view of a com-

bined bottle opener and cork remover, showing our new design,

Figure 2 is a side elevational view of the device shown in Figure 1,

Figure 3 is an exploded view of the device shown in Figure 1,

Figure 4 is a side elevational view of the device as shown in Figure 3.

We claim:

The ornamental design for a combined bottle opener and cork remover, as shown.

FRITZ KAHLEN.
PETER P. JORDAN.
